UNITED STATES PATENT OFFICE.

CLAUDE L. BUNTE, OF RAWLINS, WYOMING.

PARACHUTE TOY.

Application filed April 8, 1921. Serial No. 459,632.

To all whom it may concern:

Be it known that I, CLAUDE L. BUNTE, a citizen of the United States, residing at Rawlins, in the county of Carbon and State 5 of Wyoming, have invented a new and useful Improvement in a Parachute Toy, of which the following is a specification.

My invention relates to toys, advertising or display devices, and the like, and has 10 particular reference to a projectile capable of containing the display or other matter which will, at a predetermined time, open for the discharge of its contents.

The invention includes providing a form 15 of projectile which will cause a minimum opposition of the air to its passage and means for maintaining it intact until opened and for opening it at a predetermined time.

As a part of my invention, I have, also, provided means for throwing the projectile into the air which causes it to rotate thereby 20 steadyng its flight, and at the same time causing it to unwind the means for holding the parts of the projectile intact.

25 Among the divers objects of my invention is the provision of a projectile formed of a plurality of cup-like shells that are releasably connected together so that when thrown into the air by the projecting device will rotate 30 and thus unwind or release the securing means so that when the projectile shall have attained the desired altitude the parts of the shell will be open and discharge the contents which will fall to the ground by gravity.

35 The contents or charge in the projectile may be in the form of confetti, advertising novelties, pyrotechnics, or articles of a similar nature. I may also place within the shell of the projectile a parachute for the amusement 40 of children, in which event I prefer to connect the projectile parts to the carrier strings of the parachute in order to stabilize the descent of the parachute and to prevent the separation or loss of the divers parts 45 of the structure. Another object of my invention is to provide a suitable holder from which the projectile may be thrown into the air whereby the shell will be caused to ascend to a greater altitude than could be accomplished by the action of the person's arm and hand alone. Also in connection with the 50 holder and "thrower," I have provided means which will cause the rotation of the shell or projectile during its ascent so that 55 the retaining means for the parts of the shell may be unwound during the ascent so

that the shell parts are released at a desired or predetermined height. This permits the person operating the apparatus to determine in advance the manner of setting the release 60 of the contents of the shell so that they may be discharged when the shell is at its greatest altitude. Other advantages of the device will be apparent to persons familiar with this art, and I prefer to accomplish the 65 divers objects of my invention in substantially the manner hereinafter fully described, and as more particularly pointed out in the claims.

Reference will now be made to the accompanying drawings that form a part of this specification, which are, in a sense, diagrammatical.

In the drawings:

Figure 1 is a side elevation of the holder 70 and throwing device with the projectile shell retained therein.

Figure 2 is a top plan of the structure, shown in Figure 1.

Figures 3 and 4 are fragmentary details 80 of the elements of the thrower for causing the rotation of the projectile, the latter view being taken on line 4-4, Figure 3.

Figure 5 is a transverse sectional view 85 of the shell taken on line 5-5, Figure 1, and enlarged.

Figure 6 is a view of the shell opened with the parachute inflated, as in descent.

Referring more particularly to Figures 1, 2 and 5, it will be seen that the projectile 90 comprises two similarly shaped shells or halves 5, 5, the rims 6 whereof are substantially flat and fit against each other to complete the shell and the concaved portions 95 face each other. This shell, as seen in Figures 2 and 5, is of less thickness in transverse section than the diameter of either of the shell parts, the wall of the shell between rims 6 being slightly oval in section, as shown in the drawings, so as to present 100 a "streamline" contour and offer the least resistance to the air when the projectile is thrown edgewise into the air.

The manner of securing the parts of the shell together consists of a string or cord 105 7, and in order to carry out the objects of my invention, I have provided spaced notches 8, 8, in one edge of rims 6, and diametrically opposite thereto, I have provided a plurality of notches 9 closer together than notches 8 so as to provide 110 fingers or projections 10 between the same.

In placing the string upon the shells, one end is placed in one of the notches 9 and the string is given a single wind about the shell through one of notches 8 and into one 5 of the other notches 9 after which the string is threaded back and forth through the remaining notches 8 and 9 and partially around opposite sides of the fingers or projections 10, as seen in detail in Figure 2. This retains 10 the elements of the shell together and holds the end of the string from unwinding. After this has been done, the operator continues to wind the string around the shell engaging notches 8 and notches 9, as will 15 be understood, until a sufficient quantity or length of string has been unwound thereon. The number of winds or turns about the shell determines the number of revolutions the shell will make edgewise through the 20 air when in flight, and thus substantially or approximately determines the altitude at which the string will become entirely unwound and the two parts of the shell released.

25 The manner of projecting the shell into the air is either by hand or by the device shown in Figure 1. I prefer the latter for the reason that the shell is projected with greater force and more accurately, and is 30 prevented from wobbling or rotating upon other than its central transverse axis, as indicated by the broken line 11 in Figure 5. The device illustrated in Figure 1 consists of an elongated shaft or rod 12, one 35 end whereof provides a handle, and the outer end whereof is reduced, as at 13, in a concave manner. A groove 14 is made parallel with the sides of the reduced portion 13 to receive rims 6 of the shell, and a projection 15 is made adjacent the end of the reduced portion to fit a corresponding notch or recess 16 in the rims of the shell in a plane substantially at right angles to the plane of the winding string 7. A retractable or movable jaw 17 of substantially 40 triangular shape is pivoted upon shaft 12 by means of a pin 18 and the outer end of jaw 17 is reduced or concave, as at 19, substantially corresponding in curvature of the shell rim. This portion 19 of the jaw is 45 provided with a groove or channel 20 to receive the rim, and said jaw is kept normally pressed toward the shaft by means of an elastic or spring element 21 connecting the 50 jaw beyond its pivot with shaft 12.

55 It will be seen from the foregoing description that when the shell is placed in the thrower the retractable or removable jaw frictionally retains the same, and the operator can swing the shaft quickly through the air upon the decrease or stopping of which movement the friction is overcome and the shell released. Upon its release the shell will rotate upon its axis 11, owing to the movement given it by the operator and

its engagement with projection 15. As the shell ascends it rotates and string 7, owing to its friction upon the air, unwinds with each revolution of the shell until it is entirely unwound, and releases the two parts 70 of the shell. This is preferably at the highest altitude reached in its flight. The contents of the shell will then be discharged and scattered in the air, as will be understood.

75 In the event the device is used as a toy for the amusement of children and others, I may employ a parachute, which I have illustrated in Figure 6, and upon the opening of the shell the parachute body 22 becomes inflated and the shell members being secured to the carrier ropes or strings 23 will balance or stabilize the parachute, and it will descend in a slow and gradual manner. In such use, I prefer to connect the parts of 80 the shell by a cord or string 24 to prevent them being lost when falling to the ground. Divers advertising novelties may be enclosed in the shell instead of the parachute or pyrotechnic may be used for both day and 85 night display with or without the parachute. It will also be understood that the structure I have described is well adapted for use with illuminating shells, in which event the well known star shells may be used. It 90 will be understood that all this is contemplated within the scope of my invention and divers changes may be made without materially departing from the principles I have set forth in the appended claims.

95 What I claim is:

1. A toy comprising a projectile consisting of a pair of oblate semi-spheroidal shell sections, flanges on the edges of said shell sections that provide a rib on the assembled projectile; said rib provided with registering recesses, a retaining element wound about said projectile and engaging said recesses, and a holder and thrower for said projectile consisting of a pair of yielding jaws having their opposing faces grooved to receive and seat the rib of said projectile, and a projection on one of said jaws adapted to enter one of said recesses on the projectile whereby when said projectile is thrown from said holder the projection will cause the rotation thereof.

100 2. A toy comprising a projectile consisting of a pair of oblate semi-spheroidal shell sections, flanges on the edges of said shell sections that provide a rib on the assembled projectile; said rib provided with registering recesses, a retaining element wound about said projectile and engaging said recesses, a parachute connected to said shell 105 sections and enclosed within said shell sections, and a holder and thrower for said projectile consisting of a pair of yielding jaws having their opposing faces grooved to receive and seat the rib of said projectile,

and a projection on one of said jaws adapted to enter one of said recesses on the projectile whereby when said projectile is thrown from said holder the projection will cause 5 the rotation thereof.

3. A toy comprising a projectile consisting of a pair of disks of relatively shallow concavo-convex section and having flanged peripheries, said disks disposed with their 10 concaved portions facing and the flanges parallel and contacting; said flanges provided with a plurality of recesses disposed substantially diametrically opposite each other, and a cord wound transversely about said 15 disks in said recesses, a portion of said cord being laced laterally back and forth in several adjacent recesses whereby the initial end of said cord is secured in position and

prevented from unwinding until the remaining portion of the cord has been unwound. 20

4. A toy comprising a projectile consisting of a plurality of concavo-convex shell sections, flanges on the edges of said shell sections that provide a rib on the assembled projectile; said rib having a serrated portion and a recessed portion opposite thereto, and a cord wound about said projectile in said recesses with a portion laced laterally back and forth in said serrations. 25

Signed at Rawlins, county of Carbon and 30 State of Wyoming, this 2nd day of April, 1921.

CLAUDE L. BUNTEN.
